P. B. KROUT

WIRE CLAMP

Filed Sept., 20, 1924

INVENTOR:

22 PALLED BERTRAM KROUT,

by Stephen E. Raige
Attorney

UNITED STATES PATENT OFFICE.

PALLED BERTRAM KROUT, OF NARBERTH, PENNSYLVANIA.

WIRE CLAMP.

Application filed September 20, 1924. Serial No. 738,803.

To all whom it may concern:

Be it known that I, PALLED BERTRAM KROUT, a citizen of the United States, residing at Narberth, in the county of Montgomery and State of Pennsylvania, have in-

5 vented a certain new and useful Improvement in Wire Clamps, whereof the following is a specification, reference being had to the accompanying drawings.

10 My invention relates to devices for clamping, in parallel and crossed relation, wires, cables or ropes, and particularly for clamping a small cable in transverse relation with a much larger one. The form of my invention hereinafter described includes a block, of elliptical configuration, having two bolt holes extending through it, intersecting its major axis; two grooves, extending in transverse relation in said block, to 15 different depths therein, between said holes; either groove being of the larger diameter; said grooves being at right angles to each other but in unsymmetrical relation with said block; lugs upon respectively opposite 20 sides of said grooves, also in unsymmetrical relation with said block; a U-bolt adapted to extend through said bolt holes, with its bight crossing both said grooves, and having each of its ends screw threaded; and 25 nuts adapted to respectively engage said bolt screw threads; whereby a pair of wires, of respectively different diameters, may be clamped together in transverse relation to each other, by tightening said nuts. Of 30 course, each of said grooves is adapted to hold a plurality of wires which may be held in parallel relation with each other and in transverse relation with the wires in the other groove, by the same clamping operation of the nuts.

My invention includes the various novel features of construction and arrangement hereinafter more definitely specified.

In said drawings; Fig. I is a plan view 45 of a clamp conveniently embodying my invention, showing two wires, of different diameters, clamped therein in transverse relation.

Fig. II is a longitudinal side elevation of 50 the structure shown in Fig. I.

Fig. III is a longitudinal sectional view of said structure, taken on the line III, III in Fig. I.

Fig. IV is a transverse side elevation of 55 said structure.

Fig. V is a transverse sectional view of

said structure, taken on the line V, V in Fig. I.

Fig. VI is a plan view, similar to Fig. I but showing a modified form of my invention.

In Figs. I to V inclusive; the block 1, which is conveniently formed as a drop-forging of steel, of elliptical configuration, has two bolt holes 2 and 3 extending there-through intersecting the major axis of the ellipse, a deep groove 5, of large diameter extending obliquely transverse to said major axis, and a shallow, and smaller diameter, groove 6 also extending obliquely transverse to said major axis and at right angles to said groove 5. However, in view of the differences in diameters of said grooves 5 and 6; they extend in unsymmetrical relation with the major axis of said block, said groove 5 forming an obtuse angle and said groove 6 forming an acute angle with reference to said axis. The lugs 8 project from said block 1, upon respectively opposite sides of said axis, and between said grooves 5 and 6 and, of course, in unsymmetrical relation with said block. Said lugs 8 have plane faces, 9 and 10 respectively parallel with, and merging into, said grooves 5 and 6. The U-bolt 12 is adapted to extend through said bolt holes 2 and 3, with its bight 13 crossing both said grooves 5 and 6, and has each of its ends screw threaded for engagement with respective nuts 15. Said lug faces 9 and 10 serve as guides, whereby the two wires 16 and 17 may be clamped in transverse relation with each other, and in obliquely transverse relation to the major axis of said block 1, with said bolt 12 and wires 16 and 17 held against displacement between said lug faces 9 and 10.

Figs. I to V inclusive are full size illustrations of a clamp adapted to rigidly secure by means of a single three-eighth inch diameter bolt, two wires or cables respectively three-fourths of an inch and three-eighths of an inch in diameter; the wider groove 5 being the deeper one. However, the deeper groove may be the narrower one, as shown in Fig. VI.

In Fig. VI; the block 21, which is also conveniently formed as a drop-forging of steel, of elliptical configuration, has two bolt holes 22 and 23 extending through it, with two grooves 25 and 26 extending obliquely transverse to the major axis of said block, between said bolt holes; the deeper groove

25 being of smaller diameter than the groove 26, which is conveniently arranged at right angles to said groove 25. Of course, in view of the differences in diameters of said 5 grooves 25 and 26; they extend in unsymmetrical relation with said block 21, and the lugs 28, formed between said grooves, are in corresponding unsymmetrical relation with said block. That is to say, my block 21 is 10 distinguished from certain prior art structures in that the elements of form thereof upon one side of the median longitudinal plane indicated at III, III in Fig. I have no corresponding elements upon the opposite 15 side of said plane upon one continued perpendicular to that plane and at the same distance from it; the latter being characteristic of the symmetrical structures of the prior art. Said lugs 28 have plane faces, 20 29 and 30 respectively parallel with, and merging into, said grooves 25 and 26. The U-bolt 32 is adapted to extend through said bolt holes 22 and 23, with its bight 33 crossing both said grooves, and has each of its 25 ends screw threaded for engagement with respective nuts 35; whereby the wires or cables 36 and 37 may be clamped in transverse relation with each other, with said bolt and wires held against displacement between 30 said lug faces 29 and 30.

Moreover, it is to be understood that a plurality of wires, of suitable size, may be clamped in parallel relation in any of said grooves.

35 Moreover it is to be understood that I may use a bolt of J-shape and do not desire to limit myself to the described shapes or dimensions or to any other specific details of construction and arrangement herein set forth, as it is obvious that various modifications may be made therein without departing from the essential features of my invention, as defined in the appended claims.

I claim:

45 1. In a wire clamp; the combination with a metal block of elliptical configuration having two bolt holes extending through it intersecting its major axis, and two grooves extending in transverse relation to each 50 other in said block, to different depths therein, between said bolt holes; the deeper groove being of larger diameter than the other groove; said grooves being at right angles to each other but in said block; one of said 55 grooves extending at an obtuse angle to said major axis, and the other of said grooves extending at an acute angle to said axis; lugs upon respectively opposite sides of said grooves, a U-bolt adapted to extend through 60 said bolt holes; with its bight crossing both said grooves, and having each of its ends screw threaded; and nuts adapted to respectively engage said bolt screw threads; whereby two wires, of respectively different 65 diameters, may be clamped together in trans-

verse relation to each other, by tightening said nuts.

2. In a wire clamp; the combination with a metal block having two bolt holes extending through it intersecting its major axis, 70 and two grooves extending in transverse relation to each other in said block, to different depths therein, between said bolt holes; the deeper groove being of larger diameter than the other groove; one of said grooves 75 extending at an obtuse angle to said major axis, and the other of said grooves extending at an acute angle to said axis; lugs upon respectively opposite sides of said grooves; a U-bolt adapted to extend through said bolt 80 holes, with its bight crossing both said grooves, and having each of its ends screw threaded; and nuts adapted to respectively engage said bolt screw threads; whereby two wires, of respectively different diameters, 85 may be clamped together in transverse relation to each other, by tightening said nuts.

3. In a wire clamp; the combination with a metal block having two bolt holes extending through it, and two grooves extending 90 in transverse relation to each other in said block, to different depths therein, between said bolt holes; the deeper groove being of larger diameter than the other groove; lugs upon respectively opposite sides of said 95 grooves; a bolt adapted to extend through said bolt holes, and crossing both said grooves; and a nut adapted to engage said bolt; whereby two wires, of respectively different diameters, may be clamped together 100 in transverse relation to each other, by tightening said nut.

4. In a wire clamp; the combination with a metal block having two bolt holes extending through it, intersecting its major axis, 105 and two grooves extending in transverse relation to each other; of lugs upon respectively opposite sides of said grooves, each of said lugs having inclined faces respectively merging into said grooves; a U-bolt adapted 110 to extend through said bolt holes, with a bight crossing said grooves and having each of its ends screw threaded; and nuts adapted to respectively engage said bolt screw threads; whereby wires may be clamped in 115 said grooves in transverse relation to each other.

5. In a wire clamp; the combination with a metal block having a bolt hole extending through it, and two grooves extending in 120 transverse relation to each other in said block, to different depths therein; the deeper groove being of larger diameter than the other groove; lugs upon respectively opposite sides of said grooves; a bolt adapted to 125 extend through said bolt hole, and crossing both said grooves; and a nut adapted to engage said bolt; whereby wires may be clamped together in transverse relation to each other.

6. In a wire clamp; the combination with a metal block having a bolt hole extending through it, and two grooves extending in transverse relation to each other in said block, to different depths therein; the deeper groove being of larger diameter than the other groove; lugs upon respectively opposite sides of said grooves; a bolt adapted to extend through said bolt hole, and crossing both said grooves; and a nut adapted to en-

gage said bolt; whereby wires may be clamped together in said grooves.

In testimony whereof, I have hereunto signed my name at Philadelphia, Pennsylvania, the 18th day of September, 1924.

PALLED BERTRAM KROUT.
